UNITED STATES PATENT OFFICE.

CHARLES SMITH AND JOSEPH HUTCHINSON, OF CHICAGO, ILLINOIS.

GRATE-BAR.

SPECIFICATION forming part of Letters Patent No. 286,083, dated October 2, 1883.

Application filed August 4, 1883. (No model.)

To all whom it may concern:

Be it known that we, CHARLES SMITH and JOSEPH HUTCHINSON, of Chicago, county of Cook, and State of Illinois, have invented 5 certain new and useful Improvements in Grate-Bars, of which the following is a full, clear, and exact description, that will enable others to make and use the same, reference being had to the accompanying drawings, forming a part 10 of this specification.

This invention relates to improvements in grate-bars for smoke-consuming furnaces; and it consists of a hollow bar provided with a number of hollow lugs projecting upward from 15 the upper surface of said bar, said lugs being perforated on the side next the fire for the purpose of discharging the heated air at a point above the level of the grate-bars.

Figure 1 is a longitudinal section of a boiler-furnace embodying our improved feature; Fig. 2, a transverse section, and Fig. 3 a view in perspective, of a portion of a boiler-furnace.

Referring to the drawings, A represents a boiler; B, the inclosing-walls; a, the boiler-front; a', the bridge-wall; C, the ash-pit, and D the combustion-chamber. One of the hollow bars E is placed at each side of the furnace, the intermediate grate-bars, F, being of the usual or any other pattern. The bars E may 25 be so constructed as to take the air from the ash-pit through the under side or in at the side of the bar next the inclosing-walls through the air-passage b. The upper side of the bar E is provided with the upward-projecting hollow 30 lugs d, which are perforated on the side next the fire, and through which the air is discharged into the combustion-chamber. These lugs are of a rectangular form, and are arranged at regular intervals from the front end 35 of the bar back to a point about one-third of its length.

It has been learned by practical experiments that the portion of air admitted through the side walls and hollow bars should be nearer 45 the front end of the furnace, and for this reason the hollow bars are not provided with lugs or openings into the furnace beyond a certain

point. The lugs projecting above the level of the grate-bars become very hot, so that the air in coming up from the hollow bars is 50 heated to a high degree of temperature before it mingles with the other products of combustion in the furnace.

This form of our device is readily and quickly placed in position for service, for where the 55 furnace is already constructed all that is necessary is the removal of a grate-bar from each side of the fire-box, and then replacing the same with our improved bar adapted to take air in on the under side.

In constructing new furnaces, or in altering over old ones, when it is desired to take the atmospheric air through passages in the side walls, the hollow bars may be set into the wall, so as to take the air altogether from the side 65 instead of the bottom of the hollow bar.

The bridge-wall is built close up to the boiler, and is provided with the square opening d', through which the flames escape from the combustion-chamber.

Having thus described our invention, what we claim as new, and desire to secure by Letters Patent, is—

1. A hollow grate-bar adapted to take air from the bottom or side next the inclosing-walls, and provided with a number of hollow perforated lugs projecting upward from and arranged at regular intervals along a part of said bar, substantially as and for the purpose set forth.

2. The combination, with an air-passage located in the side walls inclosing the furnace, of a hollow grate-bar placed against said walls at each side of the furnace, and provided with hollow perforated lugs projecting from the upper surface of said bar, and discharging heated air into the furnace above the level of the grate-bars, substantially as and for the purpose set forth.

CHARLES SMITH.

JOSEPH HUTCHINSON.
